[57] ABSTRACT

A pen includes a lower barrel member having a lower annular chamber, a longitudinal passageway extending from the lower chamber to the exterior, an upper chamber located above the lower chamber and communicating with the lower chamber by a second longitudinal passageway 180° offset from the first passageway. A coaxial ink carrier extends from a writing element at the top of the barrel section through the upper chamber and an upper restricted base to define a narrow venting passage. The ink carrier enters an ink reservoir which may be of the cartridge type pierced by piercing tube at the top of the barrel section or which may include an ink bottle to which the barrel member is attached by a screw cap. A further embodiment includes a plastic sleeve surrounding the ink carrier along the lower and upper chambers.

WRITING INSTRUMENT

CROSS REFERENCE TO RELATED APPLICATIONS

This is a continuation-in-part of my now abandoned application Ser. No. 389,296, filed Aug. 17, 1973, which in turn was a continuation of application Ser. No. 221,201 filed Jan. 27, 1972, now abandoned.

BACKGROUND OF THE INVENTION

The present invention relates generally to improvements in writing or marking implements and it relates particularly to an improved fountain pen structure which may be employed with inks of a wide range of viscosities and compositions and with different types of writing elements such as balls, nibs, felt tips and the like.

An important parameter in the satisfactory operation of a fountain pen, whether of the ball point, conventional nib, felted or capillary tip or the like and of the cartridge, sack or other ink reservoir type is the proper regulated feed of the ink to the writing element so that the ink may be suitably transferred to any ink receiving substrate. In order that the ink be uniformly delivered to the writing element, as demanded, it is necessary that the ink reservoir be properly vented to maintain an optimum ink pressure. This venting heretofore depended on the viscosity and composition of the ink, and with many types of inks proper venting was impossible or very difficult to achieve with the result that fountain pens are limited to only certain types of inks. Thus the venting systems in the conventional fountain pens possess numerous drawbacks and disadvantages and leave much to be desired.

SUMMARY OF THE INVENTION

It is a principal object of the present invention to provide an improved writing implement.

Another object of the present invention is to provide an improved fountain pen.

Still another object of the present invention is to provide an improved fountain pen structure, which may be employed with inks of a wide range of viscosities as well as with different writing elements.

A further object of the present invention is to provide an improved fountain pen having an ink reservoir venting system, which permits its use with a great variety of writing elements, inks and ink reservoirs.

Yet another object of the present invention is to provide an improved writing implement that uses a low viscosity ink that is ready to use at all times and which does not dry out.

Still a further object of the present invention is to provide a device of the above nature, characterized by its reliability, ruggedness, simplicity, versatility, adaptability and low cost.

The above and other objects of the present invention will become apparent from a reading of the following description taken in conjunction with the accompanying drawings which illustrate preferred embodiments thereof.

In a sense the present invention is based on the discovery that an optimum venting of an ink reservoir in a fountain pen is achieved by providing communication between the ink reservoir and the exterior through a venting system including an enlarged circumferentially extending chamber, a first passageway providing com-

munication between the chamber and the exterior and a second passageway connected to the chamber at a point transversely offset from the first passageway and communicating with the ink reservoir. In its preferred form, the improved writing implement includes an upper separable ink reservoir, a lower barrel member supporting at its tip, a writing element, such as a ball, nib or porous tip, and an ink carrier extending coaxially from the writing element to the ink reservoir. The ink carrier may be surrounded partially by a sleeve which limits the air passage to the ink reservoir. The chamber is of generally annular configuration and is formed in the barrel member and the first and second passageways are circumferentially offset between 90° and 180° and extend longitudinally in the barrel member. The second passageway communicates with the ink reservoir through a second enlarged chamber which communicates with the ink reservoir through a third passageway. The ink reservoir may be a conventional ink cartridge pierced in any suitable manner or may be a receptacle having a threaded portion which is separably engaged by an apertured screw cap which couples the barrel member to the receptacle.

The writing implement employing the improved venting system permits the use of the pen with inks of different viscosities and compositions, with different forms of ink reservoirs and with different types of writing elements. The ink feed is uniform and optimum and the pen's writing and marking characteristics are highly superior and do not dry out.

BRIEF DESCRIPTION OF THE DRAWINGS

FIG. 1 is a front elevational view, partially in medial longitudinal section, of a ball point pen of the cartridge type employing the present invention and illustrated in a cartridge unpierced condition;

FIG. 2 is a side elevational view thereof, partially in longitudinal section and illustrated in an operable condition;

FIG. 3 is a fragmentary side elevational view thereof in a capped condition;

FIG. 4 is an enlarged sectional view taken along line 4—4 in FIG. 2;

FIG. 5 is a longitudinal sectional view of another embodiment of the present invention;

FIG. 6 is a front elevational view, partially in section, of still another embodiment of the present invention;

FIG. 7 is a front elevational view of another embodiment of the present invention;

FIG. 8 is a fragmentary front elevational view, partially in section of a further embodiment of the present invention;

FIG. 9 is an enlarged fragmentary sectional view of the lower portion of another embodiment of the present invention; and

FIG. 10 is an enlarged sectional view taken along line 10—10 in FIG. 9.

DESCRIPTION OF THE PREFERRED EMBODIMENTS

In the following embodiments like numerals indicate like parts.

Referring now to the drawings, particularly FIGS. 1 to 4 thereof, which illustrate a preferred embodiment of the present invention, the reference numeral 10 generally designates the improved writing implement in the form of a replaceable liquid ink cartridge ball point

pen. The pen 10 includes an upper barrel section 11 closed at its top and internally threaded at its bottom and a lower barrel section 12 which releasably engages the threaded bottom portion of upper barrel section 11. An ink cartridge 13 of known construction is replaceably housed in barrel section 11 and is of cylindrical configuration and provided with an annular heavy bottom wall closed by a pierceable or fragile panel 14.

The bottom barrel section 12 comprises an upper sleeve member 16 provided with an axial cylindrical bore 17 extending from the bottom of sleeve member 16 to an upper transverse wall 18. Integrally formed with and projecting axially upwardly from wall 18 is a tubular cartridge piercing member 19 provided with a peripheral abutment shoulder 20 between its ends. The upper end of piercing member 19 is bevelled to a sharp edge and an axial bore 21 having a vent passage defining longitudinal channel 22 in its face is formed in piercing member 19 and wall 18. The upper outside face 23 of barrel member 12 is externally threaded and engages the threaded portion of barrel section 11 and is delineated from the bottom outside face 24 by an upwardly directed peripheral shoulder, the face 24 converging downwardly and terminating in an outwardly flared lip.

The barrel section 12 also comprises a core member 26, which includes an upper cylindrical portion 27 tightly engaging the lower half of bore 17 to define an upper venting chamber 28. The lower portion 29 of core member 26 tapers downwardly to a tip. An axial bore 30 is formed along the full length of core member 26 and is of reduced diameter at the bottom thereof, being separated from the upper portion of the bore by a peripheral shoulder.

As part of the venting system which characterizes the present structure, there is formed in the upper outer face of core member 26, a peripheral channel or groove which, with the confronting face of the bore 17, defines an annular enclosed chamber 32. A longitudinally extending first passageway defining groove 33 is formed in the outer face of cylindrical section 27 and extends from the bottom thereof to chamber 32 to provide communication between the chamber 32 and the exterior. A second longitudinal passageway 34 is defined by a longitudinal groove formed in the upper part of the outer face of core member 26, between chamber 32 and the top of core member 26, and provides communication between chambers 28 and 32. The passageways 33 and 34 are diametrically opposed, it being understood that they may be circumferentially offset relative to each other less than 180°, for example 90°, but that they should be relatively offset. Moreover, more than one of each passageway 33 and 34 may be provided, but they should be each relatively offset from each other.

The lower barrel section 12 carries a writing assembly, which may be of conventional construction and includes a hollow or tubular tip 36 having an upper portion 37 tightly engaged by the reduced bottom section of bore 30. A writing or ink transfer element 38, such as a ball, is rotatably supported by the tapered lower end of tip 36. An ink carrier 39 of the capillary or other known type engages and extends from the lower end of tip 36 loosely through the bore 21 to the top face of piercing member 19, and conducts ink from the interior of cartridge 13 to the writing element. A clip carrying cap 35 of known construction is provided to close

the writing end of the pen 10, when the pen is not in use.

The pen 10 is employed in the known manner, the cartridge 13 being coupled to the ink carrier 39 by turning and contracting the barrel sections 11 and 12 so as to cause the penetration of piercing member 19 into the cartridge 13. The cartridge 13 is vented by exposure to the exterior through passageway 22, chamber 28, passageway 34, chamber 32 and passageway 33. By reason of the construction of the venting system, a uniform regulated optimum flow of ink from the ink reservoir to the writing element 38 is achieved in response to the requirements of the writing element.

In FIG. 5 of the drawings, there is illustrated another embodiment of the present invention, which differs from that first described primarily in the construction of the ink reservoir and barrel coupling. Specifically, the improved pen 40 includes an ink containing reservoir defining bottle 41 provided with an externally threaded neck 42. A tubular barrel sleeve member 43 is provided at its top with a peripheral flange 44 which separably abuts the end face of bottom neck 42. A screw cap 46 includes an internally threaded skirt wall 45 which separably engages the threaded neck 42 and a centrally apertured end wall which engages sleeve 43 and the underface of flange 44 to permit a separable liquid-tight coupling between bottle 41 and sleeve 43. Integrally formed with the sleeve 43 intermediate its ends is an axially bored heavy transverse wall 47 having a longitudinal passageway defining channel formed in the axial bore corresponding to channel 22.

An assembly of a barrel core member 48, writing element 49 and its associated holder and an ink carrier 50, similar in construction and association to core member 26, writing element 38 and ink carrier 39, earlier described is supported by the lower part of the sleeve 43. The ink carrier 50 extends through the bore in wall 48 to shortly above its top face and the top face of core member 48 delineates a chamber 51 in sleeve 43 below wall 48. As in the first embodiment, an annular chamber 52 is formed in the upper part of core member 48 which communicates with chamber 51 and the exterior by circumferentially offset passageways corresponding to passageways 34 and 44. It should be noted that screw cap 43 may be integrally formed with sleeve member 43 and the flange 44 obviated. Further, the length of sleeve member 43 may be reduced and the wall 47 may join the end wall at the integral cap section with the ink carrier 50 projecting to the top of the cap section.

Except for the coupling of the bottle 41 to the sleeve barrel 43, as explained above, the operation of pen 40 is similar to that of pen 10, first described.

The pen 52 illustrated in FIG. 6 of the drawing differs from the pen 40 last described only in that instead of the ball writing element there is employed a longitudinally porous or felt type writing element 53. The writing element 53 is of known construction and engages the bottom end of an ink carrier 54 which corresponds to ink carrier 50. In all other respects of construction and operation the pens 40 and 52 are similar.

In the embodiment of the present invention shown in FIG. 7, a nib 54 and the conventional ink carrier and ink feed are substituted for the writing elements and ink carriers of the pens 40 and 52 and the pen 56 shown in FIG. 7 is otherwise similar to the pens 40 and 52, the sleeve 57 being similar to sleeve 43 and the core member 58 being similar to the core member 26 except in-

sofar as it is modified to accommodate the nib 54. The reservoir venting system of the pen 56 is similar to those of pens 40 and 52.

The pen 59 illustrated in FIG. 8 differs from the pens 49 and 52 in the construction of the ink reservoir and the association therewith of the ink carrier. In the pen 59 the ink reservoir comprises a cylindrical container 60 containing a soft porous material heavily impregnated with a liquid ink. The container 60 is externally threaded proximate its open end and has a barrel member 61 separably coupled thereto by a screw cap 63, barrel member 61 and screw cap 63 corresponding to barrel member 43 and screw cap 46 and these too may be integrally formed. An ink carrier 65 extends from the writing element, not shown, into the container 60 and in all other respects, the pen 59 is similar to pens 40 and 52 in construction and operation.

FIGS. 9 and 10 illustrate a further embodiment of the present invention which differs from the first described embodiment primarily in the addition of sleeve 70 surrounding ink carrier 39. Sleeve 70 tightly engages the upper portion 37 of tip 36, and as shown is mounted between portion 37 and the reduced bottom of bore 30 of core member 26, so as to form a seal. The inner peripheral surface of sleeve 70 is advantageously spaced from the outer surface of ink carrier 39 to form a pocket 74. Sleeve 70 extends from the lower portion of core member 26 along bore 30 and into chamber 28 and abutting the upper wall 18 of upper sleeve member 16. The upper edge of sleeve 70 is tapered, at one end, as indicated at 72, to reduce the air flow into cartridge 13, as will be discussed hereinafter with respect to the venting of pen 10. The space between the outer peripheral surface of sleeve 70 and the inner surface of bore 30 is dimensioned so that any ink trapped therebetween will be trapped there or at most will flow out very slowly by the nature of the capillary action.

As an example of the dimensions of the sleeve 70 and ink carrier 39, an embodiment that provided satisfactory results utilized a diameter of sleeve 70 of 0.0950 inch and an outer diameter of ink carrier 39 of 0.0313 inch providing a radial space of 0.0319 inch. The clearance of the ink carrier 39 within the axial bore 21 is about 0.005 inch on all sides. Also, as noted in ink carrier 39 is slightly chamfered along one edge to aid in breathing as illustrated in FIG. 2.

The pen illustrated in FIGS. 9 and 10 is employed in the manner described above with respect to the first embodiment described above. The cartridge 13 is vented by exposure to the exterior through a torturous passageway which allows air to enter as required, but no liquid or ink to flow out and leak. The air enters through longitudinal passageway 33 into annular chamber 32 across and through passageway 34 into chamber 28 which recrosses into offset passageway 22 between the top edge 72 of sleeve 70 and surface 18 defining chamber 28. This venting provides a uniform regulated flow of ink from reservoir 13 to the writing element 38 without leaking. Any excess ink from carrier 39 flows from the outer surface of 39 into the space between the outer surface of carrier 39 and sleeve 70 and is trapped within the space 74 therebetween. The bottom of sleeve 70 is tightly affixed to portion 37 of tip 36 to prevent any ink flow there. This ink build-up in space 74 keeps carrier 39 moist adjacent the tip 38 and therefore prevents any drying of the tip between periods of use. The pen is ready to use at all times. If by any chance

any ink does enter chamber 28, it will flow down by capillary action between the outer surface of sleeve 70 and the inner surface of bore 30 and remain trapped there. The ink does not flow into passageway 34 by reason of the outside air pressure from annular chamber 32 and the attraction of the capillary passageway between bore 30 and the outer surface of sleeve 70. Further, the ink trapped between the carrier 39 and the sleeve 70 prevents any air travelling down carrier 39 to the point 38.

The present invention allows free interchangability of ink supplies, such as illustrated in FIGS. 5-8. The ink supplies or reservoirs are the ink containers themselves, so that various colors and types of ink can be stored by the user and available when needed. Fast drying inks can be used with various types of nibs and writing tips.

While there have been described and illustrated preferred embodiments of the present invention, it is apparent that numerous alterations, omissions and additions may be made without departing from the spirit thereof.

What is claimed is:

1. A writing implement comprising a writing element at the lower end, an ink reservoir, an ink carrier providing communication between said reservoir and said writing element and means for venting said ink reservoir defined by axially spaced lower first and upper enlarged second chambers, at least one first passageway extending longitudinally from said first chamber and communicating with the exterior of said implement for providing communication between the exterior and said first chamber, at least one second passageway extending between and communicating with said first and second chambers, said second passageway including portions transversely offset relative to all of said first passageways and a third passageway delineated by said ink carrier and extending along the length thereof and providing communication between said second chamber and said ink reservoir.

2. The writing implement of claim 1 wherein said ink reservoir, ink carrier and writing element are longitudinally aligned and said chamber are of annular configuration and coaxial with said ink carrier.

3. The writing implement of claim 2 wherein said first and second passageways are circumferentially relatively offset and extend in longitudinally opposite directions from said first chamber.

4. The writing implement of claim 3 wherein said first and second passageways are circumferentially offset between 90° and 180°.

5. The writing implement of claim 2 further including a tubular sleeve surrounding said ink carrier and having its lower end proximate the writing element and its upper end extending into the second chamber, said second chamber having an upper wall.

6. The writing implement of claim 5 wherein said sleeve is spaced from said ink carrier and its upper end being beveled and abutting the upper wall of said second chamber.

7. The writing implement of claim 3 including a lower barrel section, said writing element being located at the lower end of said lower barrel section and said ink carrier extending coaxially through said lower barrel section into communication with said ink reservoir, said first and second passageways and said first chamber being formed in said lower barrel section.

8. The writing implement of claim 7, wherein said lower barrel section comprises an axial longitudinally extending tubular core member and a coaxial longitudinally extending outer sleeve member engaging said core member, said first chamber and said first and second passageways being formed between the confronting peripheral faces of said core and outer sleeve members.

9. The writing implement of claim 8 wherein said core member projects below said outer sleeve member and said outer sleeve member projects above said core member and delineates said second chamber disposed above said first chamber said outer sleeve member having an upper restricted axial passageway communicating with said second chamber, said ink carrier extending through said restricted axial passageway and being of lesser transverse cross section to delineate therewith

said third passageway.

10. The writing implement of claim 1 including a lower barrel section having said first chamber and said first and second passageways formed therein and coaxially supporting said writing element and ink carrier, said ink reservoir comprising an ink receptacle and including means for separably connecting said barrel section and ink receptacle.

11. The writing implement of claim 10 wherein said ink receptacle comprises an externally threaded neck and said connecting means comprises a screw cap releasably engaging said threaded neck and separably securing said barrel section thereto in liquid tight communication with said barrel section.

12. The writing implement of claim 11 wherein said screw cap and barrel section are integrally formed.
